INVENTOR.

BY

Shephard & Campbell ATTORNEYS.

UNITED STATES PATENT OFFICE.

DWIGHT W. GODARD, OF AURORA, ILLINOIS.

MARCH-FOLIO HOLDER.

1,388,333.

Specification of Letters Patent. Patented Aug. 23, 1921.

Application filed October 7, 1920. Serial No. 415,441.

To all whom it may concern:

Be it known that I, DWIGHT W. GODARD, a citizen of the United States, residing at 325 Spruce street, Aurora, in the county of 5 Kane and State of Illinois, have invented certain new and useful Improvements in March-Folio Holders, of which the following is a specification, reference being had therein to the accompanying drawings.

10 This invention relates to a march folio holder adapted to receive a sheet of music to hold the same in such position that it may be seen by the musician while at the same time it will be protected from the weather 15 and from dislodgment by gusts of wind or otherwise. It is a primary object of the invention to provide a folio holder of the character indicated constructed in such manner that it will be of very light weight; 20 will be of pleasing and ornamental appearance; will be flexible and easily handled and will comprise a transparent portion which while permitting the musician to see the inclosed music, will not be of such nature as to be likely to be fractured.

25 It is a further object of the invention to provide a folio holder of the character indicated having means for easily and quickly mounting the same upon the usual music

30 lyre which is at present commonly employed to hold the music.

Further objects and advantages of the invention will be set forth in the detailed description which now follows:

35 In the accompanying drawing in which like numerals of reference designate corresponding parts throughout the several views,

Figure 1 is a front elevation of a folio 40 holder constructed in accordance with the invention;

Fig. 2 is a rear elevation thereof; and

Fig. 3 is a perspective view with the folio opened out ready to receive a sheet of music.

45 The main body of the folio holder is formed of soft pliable and light weight leather and comprises a back 5, a front 6 and a flap 7 that is adapted to fold over the back 5. The flap and back have co-operating 50 members 8 and 9 which complementally constitute a snap fastener to hold the device in the closed position illustrated in Fig. 2. The front 6 is cut out to form a sight opening 10 which occupies substantially the en-

tire area of the front and is covered by a 55 sheet of flexible transparent material 11, for example, celluloid. When in use a sheet of music indicated at 12 is placed within the holder in such manner that it will be visible through the transparent material 11 as illustrated in Fig. 1 and the flap 7 is folded down over the back 5 and secured in such folded over position by the snap fastening elements 8 and 9. The device as a whole may then be mounted upon an ordinary music lyre by 60 means of a pocket formed within a sheet 13 of a leather which corresponds in appearance to the material of which the back 5 is made. This sheet is stitched along three 65 of its sides as indicated at 14 to the back 5. 70 However it is not stitched along its lower edge and thus a pocket is formed that is open at the bottom and into which the music lyre may be slipped.

From the foregoing description it will be 75 seen that simple and efficient means are herein provided for accomplishing the ends sought.

However, it is to be understood the invention is not limited to the precise construction set forth but that it includes 80 within its purview whatever changes fairly come within either the terms or the spirit of the appended claim.

Having described my invention, what I 85 claim is:

A device of the character described 90 formed of an integral flexible material and comprising a back, a front and a flap, said front having a sight opening formed therein covering substantially its entire area, a sheet of flexible transparent material for covering the sight opening, said transparent material 95 lying directly adjacent the inner face of the back over its entire area so that a music sheet disposed between the transparent material and the back will be visible through said transparent material over the entire surface of the latter and a sheet of material secured to the outer face of the back along 100 both of its sides and across its upper edge and having its lower edge left free to thereby form a pocket for the reception of a supporting element.

In testimony whereof I hereunto affix my 105 signature.

DWIGHT W. GODARD.
